(57) **CLAIM**

The ornamental design for a junction box, as shown and described.

DESCRIPTION

FIG. 1 is a top side perspective view of a first embodiment of a junction box showing our new design;

FIG. 2 is an opposite top side perspective view thereof;

FIG. 3 is a bottom side perspective view thereof;

FIG. 4 is an opposite bottom side perspective view thereof;

FIG. 5 is a top side perspective view of a second embodiment of a junction box showing our new design;

FIG. 6 is an opposite top side perspective view thereof;

FIG. 7 is a bottom side perspective view thereof;

FIG. 8 is an opposite bottom side perspective view thereof;

FIG. 9 is a front elevational view of a third embodiment of a junction box showing our new design;

FIG. 10 is a side view thereof;

FIG. 11 is a top plan view thereof;

FIG. 12 is an opposite side view thereof;

FIG. 13 is a rear elevational view thereof;

FIG. 14 is a bottom plan view thereof;

FIG. 15 is a top side perspective view of a fourth embodiment of a junction box showing our new design;

FIG. 16 is an opposite top side perspective view thereof;

FIG. 17 is a bottom side perspective view thereof;

FIG. 18 is an opposite bottom side perspective view thereof;

FIG. 19 is a top side perspective view of a fifth embodiment of a junction box showing our new design;

FIG. 20 is an opposite top side perspective view thereof;

FIG. 21 is a bottom side perspective view thereof; and,

FIG. 22 is an opposite bottom side perspective view thereof.

The broken lines shown in FIGS. 1-22 are included for illustrative purposes only and form no part of the claimed design.
